UNITED STATES PATENT OFFICE.

RUBEN JURY, OF SANDUSKY, MICHIGAN, ASSIGNOR OF ONE-THIRD TO WILLIAM WAKEFIELD AND ONE-THIRD TO ARCHIBALD L. GILLAM, BOTH OF SANDUSKY, MICHIGAN.

DIPPER-EXCAVATOR.

1,076,676.

Specification of Letters Patent.

Patented Oct. 28, 1913.

Application filed November 9, 1912. Serial No. 730,321.

To all whom it may concern:

Be it known that I, RUBEN JURY, a citizen of the United States, residing at Sandusky, county of Sanilac, and State of Michigan, 5 have invented certain new and useful Improvements in Dipper-Excavators, of which the following is a specification.

This invention relates to dipper excavators.

10 The present invention has for its object the provision of a novel excavator of the dipper type, particularly adapted for digging ditches or trenches in which sewer pipes, tile, and the like may be laid, which 15 may be constructed at relatively small expense, will have few parts and be light, durable, strong, and require but one man for its operation, while having an excavating capacity several times that of the ordinary 20 trench or ditch excavators heretofore known to the art.

A further object of the invention is the provision of an excavator adapted to automatically set or position itself for carrying 25 out the excavating operation and which will, after the dipper has been filled, automatically dump the contents thereof.

Another object is the provision of a novel excavator whose mechanism is so arranged 30 and constructed that it may be readily moved from place to place and made ready for operation with the expenditure of a small amount of time and labor and, further, which will be adapted to operate on much 35 softer ground than is possible with other excavators on account of the lightness of the machine.

A still further object is to provide an excavator of novel construction arranged on 40 its supporting frame in such manner that the excavating operation, instead of tending to tilt the frame as with those excavators whose dipper stems extend out beyond the frame, tends to more firmly retain the entire 45 excavator in position, this to be accomplished by the disposition of the excavating mechanism at an intermediate part of the frame in such position that the excavating of the earth is beneath the frame instead of laterally beyond one side or end thereof as has 50 heretofore generally been the case.

Further objects are the provision of a novel dipper excavator having new means whereby the depth of the trench or ditch excavated may be regulated; and one which 55

will be adapted to clean out from the ditch or trench any loose dirt or material which has fallen thereinto after a preceding excavation has been made by the dipper.

The invention also has for its object the provision of a novel excavating mechanism embodying rockers mounted and combined with a new form of dipper stem and with locking and unlocking devices of novel construction whereby a relatively long sweep of 65 the dipper and a great leverage thereon are obtained and by which the mechanism is entirely automatic in its operation of positioning itself for the beginning of the excavating operation which may then be carried on 70 by the application of suitable power.

The invention is set forth hereinafter in its preferred embodiment and the novel features and combinations are recited in the appended claims.

75 In the accompanying drawings:—Figure 1 is a side elevation of the complete excavator with the rockers and dipper stem raised ready to descend for positioning of the dipper for excavating purposes, upon paying 80 out of the power cable; Fig. 2, a similar view with the power cable paid out and the dipper partially raised; Fig. 3, a similar view with the dipper in position to begin excavating; Fig. 4, an end elevation looking toward the 85 right hand end of the machine; Fig. 5, a detail perspective of the latching mechanism, the latches being shown thrown back to better illustrate the construction.

The main frame of the machine 1 is of 90 open, substantially rectangular form so that the excavating mechanism can operate centrally thereof and the dipper and its stem pass freely up and down through the frame as shown in Figs. 2 and 3. The frame is 95 suitably braced by crossed braces at its end parts which are located above the trucks 2 and 3 having ordinary traction wheels 4, providing means whereby the machine is supported only at its ends and may be moved 100 from place to place as the work progresses or for beginning new excavation.

Pivoted to opposite sides of frame 1 at 5 are a pair of upwardly converging rockers 6; pivoted at 7 to frame 1 are an upwardly 105 converging pair of rockers 8. The rockers 6 are pivoted at 9 to the dipper stem 10 which is provided with a section 11 composed of spaced members, providing an elongated slot or opening 12 between them, notches 13 being 110

provided in the members 11 and bolts or pins 14 extending across the space 12 and fastened to the members 11. The members 11 and a part of the dipper stem have an elongated slot 15. The bolt or fastener 16 which connects the ends of the rockers 8, passes through the slot 15, this construction permitting the dipper stem to automatically adjust itself longitudinally to make excavations 10 or cuts at successively greater depths as will appear hereinafter.

Pivoted on the fastener 16 are locking latches 17 and 18, respectively, the former being provided with a cross pin 19 adapted for reception in the notches 13, the latch 17 being adapted to be received in space 12. The latch 18 is also adapted to swing into the space 12 and to engage the members 14 to provide for the automatic longitudinal 20 feed of the dipper stem 10 to permit the dipper to make successively deeper cuts.

The dipper 20 may be of any ordinary or preferred form provided with a swinging bottom 21 having a spring latch 22 adapted 25 to keep it closed when it is excavating and rising. The latch is automatically pulled open by a chain 23 connected to the latch 18 due to the arrest of latch 18 by rockers 8 when the parts are in the position shown in 30 Fig. 1. A pin or other suitable device 18^a carried by latch 18 serves this purpose. The rockers 6 and 8 are respectively limited in their movements by chains 24 and 25 when in the positions shown in Figs. 1 and 3 and 35 chains 26 limit the play of the rockers 8 in the other direction. An operating cable 27 is connected to the dipper 20 and runs over a sheave 28 carried by an upward extension 29 of frame 1 and down to the drum 30 of 40 the engine.

Supported by frame 1 is a double inclined chute 31 (Fig. 4) whose apex 32 is disposed below the center of the dipper 20 when the latter is in the discharging position of Fig. 45 1, and consequently, the earth, stones, etc., carried by the dipper 20 discharge by gravity down said chute 31 in a divided stream and may be carried off to any desired point or allowed to remain on opposite sides of 50 the trench being dug. The chute 31 will be at such an angle and of such material that the easy gravitation of the material there-over will be insured.

Referring to Fig. 1, it will be observed 55 that the rockers 6 are inclined toward the rockers 8 and in consequence, without having to employ any weights, the weight of the dipper and the inclination of the rockers 6 causes the rockers 6 and 8, the stem 10, 60 and the dipper 20 to automatically fall by gravity, moving on the pivots 5, 7 and 9 when the cable 27 is paid out from drum 30. The machine is consequently self-setting and no power is used to position the

dipper where it will be ready to excavate, 65 power only being used to bring about the excavating operation when the dipper is in the position shown in Fig. 3 and, upon revolution of the drum 30, under any suitable control and driven in any suitable manner, 70 the dipper is caused to make its cut and to be brought to the position shown in Fig. 1, whereupon the chain 23 unlatches the dipper bottom or door and the excavated contents of the dipper discharge downwardly 75 upon the chute 31.

Assuming that the parts are in the position shown in Fig. 1, on paying out the cable 27, the rockers 6 and 8 fall toward each other, the pin 19 remaining in the notches 13 until the dipper stem has fallen to a vertical position and has passed that position in a direction to bring the dipper to the position shown in Fig. 3, but before the dipper has assumed the position shown in Fig. 3, the gravitation of the latch 17 causes the pin 19 to disengage from the notches 13. The entire dipper stem 10, 11, then having no support, the slot 15 permits the entire dipper stem and dipper to 90 drop longitudinally of itself, the walls of the slot 15 sliding over the pivot 16. The weight of the parts and the action of the rockers 6 carry the dipper stem past the vertical position and the parts are then in 95 the position shown in Fig. 3, the dipper being now ready to start excavating. The engagement of the latch 18 by gravity with the member 14 which is nearest to it constitutes an abutment to resist upward movement of the freed dipper stem 10 while the excavating is progressing as the pressure would otherwise cause the dipper and stem to lift and it would not have the proper bite on the earth. In Fig. 2, the dipper has 100 completed the excavating action and is ready to rise from the trench, the latch 18 having previously, by its gravity, disengaged from the member 14 with which it was previously engaged and, consequently, the dipper stem 110 is free to slide on the pivot 16 until the parts assume the position shown in Fig. 1, whereupon the pin 19 again engages and locks the dipper stem. The chain 23 just prior to this locking action, draws the latch 22 and the contents of the dipper discharge onto the chute 31. By providing a plurality 115 of members 14 which act as teeth, the dipper is allowed to make successively deeper cuts and at the same time to be locked against longitudinal shifting.

Being mounted to excavate between the points of support of the frame 1, the excavating operation does not cause any tendency in the machine to tilt but on the contrary, tends to more firmly hold the machine in position.

Having thus described my invention, what

I claim as new and desire to secure by Letters Patent, is:—

1. In an excavator, the combination of upright rockers mounted at different points and arranged at an angle to each other, of a dipper stem pivotally connected to both of said rockers whereby said rockers may move toward each other.
2. In an excavator, the combination of rockers mounted at different points, of a dipper stem pivotally connected to both of said rockers and also shiftably connected to one of them, and means for locking the shiftably mounted stem against movement or shifting when excavating.
3. In an excavator, the combination of rockers mounted at different points, of a dipper stem pivotally connected to both of said rockers and also shiftably connected to one of them, and means for locking the shiftably mounted stem against movement or shifting when excavating consisting of a plurality of catch members on the dipper stem and a movable latch carried by one of the rockers and adapted to engage said catch members.
4. In an excavator, the combination of upright rockers mounted at different points, a dipper stem pivoted to both of the rockers, the rockers being relatively inclined so that they will move toward each other when falling, a dipper carried by the stem, the arrangement of the parts adapting the rockers to move toward each other when falling and to automatically set the dipper and stem in position for excavating, and means for operating the dipper to perform the excavating operation and for raising it.
5. In an excavator, the combination of upright rockers mounted at different points, a dipper stem pivoted to both of the rockers and shiftably connected to one of them, the rockers being relatively inclined so that they will move toward each other when falling, a dipper carried by the stem, locking means adapted to prevent longitudinal shifting of the stem until the parts are in a predetermined position and the dipper is substantially ready to excavate, the arrangement of the parts adapting the rockers to move toward each other when falling from a raised position to an excavating position, means adapted to act when the dipper is in excavating position to lock its stem against longitudinal shifting, and means for operating the dipper to perform the excavating operation and for raising it.
6. In an excavator, the combination of rockers mounted at different points and arranged in inclined relation to each other whereby they are adapted to fold toward each other, of a dipper stem pivoted to one of the rockers and having a combined pivotal and shifting connection with the other rocker, the dipper stem having a tooth, a latch pivoted to the combined pivotal and shifting connection aforesaid and adapted to engage the tooth aforesaid, another latch pivoted to the combined pivotal and shifting connection aforesaid, a plurality of engaging devices carried by the dipper stem and with which the latch last-named is adapted to engage, a dipper carried by the dipper stem, the aforesaid parts adapting the dipper and stem to automatically fall by gravity, when released, and to assume an excavating position and the first-named latch to retain the dipper stem in locked condition until it is substantially positioned for excavating and the last-named latch to thereupon engage the plurality of engaging devices to permit the dipper to excavate without causing longitudinal movement of the dipper stem, while permitting the dipper to properly position itself, and means for operating the dipper and for raising it.
7. In an excavator, the combination with an open supporting frame, of means for sustaining end parts of said frame, upright rockers mounted on the frame and arranged in inclined relation to each other, a dipper stem carried by the rockers and adapted to be sustained above the frame, a dipper carried by said stem, said stem and rockers being adapted to operate through the frame intermediate the points of its support and in a general up and down direction, and means for operating the dipper when in excavating position and for raising it, the aforesaid arrangement of rockers and dipper stem adapting them, when released, to automatically, by gravity, position the dipper in excavating location.
- In testimony whereof, I hereunto affix my signature in presence of two witnesses.
